US00D876966S

(12) **United States Design Patent** (10) **Patent No.:** **US D876,966 S**
(45) **Date of Patent:** **** Mar. 3, 2020**

(54) **WATCH**

(71) Applicant: **Anhui Huami Information Technology Co., Ltd.**, Hefei, Anhui (CN)

(72) Inventor: **Xiaoxi Shi**, Mountain View, CA (US)

(73) Assignee: **Anhui Huami Information Technology Co., Ltd.**, Hefei, Anhui (CN)

(**) Term: **15 Years**

(21) Appl. No.: **29/666,808**

(22) Filed: **Oct. 16, 2018**

Related U.S. Application Data

(63) Continuation of application No. 29/585,632, filed on Nov. 28, 2016, now Pat. No. Des. 836,466.

(30) **Foreign Application Priority Data**

Jun. 3, 2016 (CN) 2016 3 0222192

(51) **LOC (12) Cl.** **10-02**

(52) **U.S. Cl.**

USPC **D10/30**; D14/344

(58) **Field of Classification Search**

USPC ..... (57) **CLAIM**

The ornamental design for a watch, as shown and described.

DESCRIPTION

FIG. 1 is a front view of a watch according to my new design.

FIG. 2 is a rear view of the watch of FIG. 1.

FIG. 3 is a left side view of the watch of FIG. 1.

FIG. 4 is a right side view of the watch of FIG. 1.

FIG. 5 is a top view of the watch of FIG. 1.

FIG. 6 is a bottom view of the watch of FIG. 1.

FIG. 7 is a perspective view of the front and right side of the watch of FIG. 1; and,

FIG. 8 is a perspective view of the rear and left side of the watch of FIG. 1.

The ornamental design which is claimed is shown in solid lines in the drawings. The broken lines in the drawings illustrate environment and form no part of the claimed design.

1 Claim, 7 Drawing Sheets
